UNITED STATES PATENT OFFICE.

WILLIAM BERNARD AND LEO FRANK, OF NEW YORK, N. Y.

DESIGN FOR A MATCH-SAFE.

SPECIFICATION forming part of Design No. 22,353, dated April 18, 1893.

Application filed February 23, 1893. Serial No. 463,486. Term of patent 7 years.

To all whom it may concern:

Be it known that we, WILLIAM BERNARD and LEO FRANK, residing at New York, county and State of New York, have invented and produced a new and original Design for Match-Safes, of which the following is a specification, reference being had to the drawings forming part thereof.

Figure 1 is a front view of a match safe showing our design. Fig. 2 is a side view thereof.

The main features of our design consist, briefly speaking, in a front plate having a raised ornamentation and scalloped upper end, and a back plate extended above said front plate and ornamented and shaped to correspond.

Referring by letter to the drawings, A designates a front plate, A' a back plate and A²

a bottom plate connecting the said front and back plates. The upper ends of the front and back plates may be scalloped as at a and the front surfaces of said plates may have a raised ornamentation. Extending upward from the base plate A² between the front and back 25 plates is a block A³ shown as flared outward at its top.

What we claim is—

The design for a match safe, substantially as shown and described. 30

In testimony whereof we have signed our names to this specification in the presence of two subscribing witnesses.

WILLIAM BERNARD.
LEO FRANK.
